(57) **CLAIM**

The ornamental design for a hanger, as shown and described.

DESCRIPTION

FIGS. 1 and 2 are back perspective views of the hanger; FIG. 3 is a front perspective view thereof; FIG. 4 is a back view thereof; FIG. 5 is a right side view thereof, the opposite side being identical; FIG. 6 is a front view thereof; FIG. 7 is a top view thereof; and, FIG. 8 is a bottom view thereof. The evenly spaced broken lines form no part of the claimed design; whereas, the dot- dash-dot lines depict environment that is unclaimed.

1 Claim, 4 Drawing Sheets
